(57) **CLAIM**

The ornamental design for a toothbrush body with a handle having a transparent surface in its lower portion for rendering visible handle-embedded decorations, as shown and described.

DESCRIPTION

FIG. 1 is a perspective view of a toothbrush body with a handle having a transparent surface in its lower portion for rendering visible handle-embedded decorations from above, showing my design;

FIG. 2 is a top plan view thereof;

FIG. 3 is a front view thereof;

FIG. 4 is a bottom plan side view thereof;

FIG. 5 is a right side view thereof; and,

FIG. 6 is a rear view thereof.
